UNITED STATES PATENT OFFICE

154,013

DESIGN FOR A BRASSIÈRE

Pierre Amyot, Quebec, Quebec, Canada

Application July 5, 1947, Serial No. 140,131

Term of patent 14 years

(Cl. D20—4)

To all whom it may concern:

Be it known that I, Pierre Amyot, a subject of the King of Great Britain, and resident of the city of Quebec, Province of Quebec, Dominion of Canada, have invented a new, original, and ornamental Design for Brassière, of which the following is a specification, reference being had to the accompanying drawing, forming a part thereof.

In the accompanying drawing:

The single figure is a front view of a brassière showing my new design.

The back of the garment is substantially the same as the face portion shown in the drawing.

I claim:

The ornamental design for a brassière, as shown and described.

PIERRE AMYOT.
